(57) **CLAIM**

The ornamental design for a portion of a display screen with color icon or personality assessment interface, as shown and described.

DESCRIPTION

FIG. 1 is a front elevational view of a portion of a display panel with a color icon, showing my new design; and, FIG. 2 is a front elevational view of the color icon for a personal assessment interface of the present invention. The broken line showing of the display screen in FIG. 1 is for illustrative purposes only and forms no part of the claimed design.

1 Claim, 1 Drawing SheetFIG. 1

FIG. 2
